UNITED STATES PATENT OFFICE.

MURDO JOHN MUNRO, OF HAMILTON, ONTARIO, CANADA, ASSIGNOR OF ONE-HALF TO
GEORGE ROBERT PETRIE, OF BURLINGTON, CANADA.

APPARATUS FOR ROLLING SHEET-METAL PIPE.

Application filed July 5, 1924. Serial No. 724,415.

To all whom it may concern:

Be it known that I, MURDO JOHN MUNRO, a subject of the King of Great Britain, and a resident of the city of Hamilton, county 5 of Wentworth, Province of Ontario, Dominion of Canada, have invented certain new and useful Improvements in Apparatus for Rolling Sheet-Metal Pipe, of which the following is the specification.

10 My invention relates to improvements in apparatus for rolling sheet metal pipe, such as stove pipe, and the object of the invention is to devise means whereby this class of pipe may be safely rolled in high speed 15 power-driven rolls, thus greatly increasing speed of production and reducing manufacturing cost.

My invention consists essentially of a power-driven pipe rolling apparatus provided with means for preventing the stock 20 from re-entering the rolls, all as herein-after more particularly described and illustrated in the accompanying drawings in which:

25 Fig. 1 is an end elevation of a pipe rolling apparatus constructed according to my invention looking in the direction of the arrow in Fig. 2.

Fig. 2 is a front elevation thereof, the 30 left hand side being shown in section on the staggered line 2—2 of Fig. 1.

Fig. 3 is a section on the line 3—3 of Fig. 2 to an enlarged scale.

Fig. 4 is a detached perspective view of a 35 guard apron used in my invention.

In the drawings, like characters of reference indicate corresponding parts in the different views.

40 My invention consists of a pipe rolling apparatus, indicated collectively at 1, and comprising a main frame 2 in which is mounted, in fixed bearings, a lower shaft 3.

Vertically above the shaft 3 is an upper shaft 4 journalled in bearing blocks 5 which 45 are adjustable vertically in guide-ways 6 in the frame 2, threaded spindles 7 controlling this adjustment.

A shaft 9 is journalled in vertically adjustable bearing blocks 8 at the rear of the 50 machine, the bearing blocks 8 being slidable in vertical guide-ways 10 in the frame 2

and 11 are threaded spindles controlling the adjustment of the blocks 8.

Mounted upon the parallel shafts 3, 4 and 9 respectively are rolls 12, 13 and 14. 55

From the foregoing it will be noted that the roll 12 has no adjustment while rolls 13 and 14 are adjustable vertically.

Mounted upon one end of the shafts 3 and 4 are intermeshing gears 15 and 16 60 respectively, while the end of the shaft 3 carries fast and loose pulleys 17 and 18 respectively.

It will thus be seen that the lower and upper rolls 12 and 13 are driven from the 65 shaft 3 whereas the rear roll 14 is an idler roll.

Mounted upon the main frame 2 at the front thereof, is an inclined stock-supporting table 19 which is supported upon brackets 20 secured to the main frame. 70

The table 19 is inclined downwardly and forwardly from the entrance or mouth of the rolls 12 and 13.

Secured to the main frame 2 by brackets 21 is an apron 22 which forms a protecting cover for the top and front of the upper roll 13. This apron extends downwardly in front of the roll 13 and terminates in a forwardly disposed stepped portion 23, the horizontal portion 24 of which is disposed slightly above the bottom of the upper roll 13 and the front flange 25 of which extends downwardly into spaced relation above the table 19 so as to form a 85 gap 26 between the table and said flange through which the stock 27 may pass to enter the rolls.

In Fig. 3 a sheet of metal which has partially passed through the rolls to be formed 90 into a pipe is indicated in full lines at 27 while in Fig. 1 this is indicated in broken lines and in Fig. 2 this stock is omitted entirely.

The construction and operation of my invention is as follows:

The rolls 13 and 14 would be adjusted for the desired gauge of sheet being rolled. This adjustment of the rolls 13 and 14 follows standard practice and is not a feature 100 of my present invention.

The stock to be rolled is fed from the

table 19 into the rolls and by having this table inclined upwardly towards the entrance or mouth of the rolls, the stock is assured of passing upwardly upon the idler 5 roller 14 and not downwardly thereunder.

As the curved sheet 27 passes upwardly and forwardly over the roll 13 the end of the sheet will curve inwardly and unless prevented will re-enter the mouth of the 10 rolls 12 and 13.

By the provision of my apron 22, re-entry of the sheet into the rolls is positively prevented, since the end of the sheet will engage the horizontal portion 24 of the step 15 23 and be supported thereby, and no matter how long the rolls may continue to rotate after the sheet has passed therethrough, said sheet can not positively re-enter the rolls.

It will thus be observed that the apron 20 22 with its step 23 constitutes a guard disposed in front of the entrance to the rolls which guard provides means for positively preventing the sheet from re-entering the 25 rolls.

Hitherto the rolling of stove pipe has been done entirely upon hand-driven machines at low speed, since it has not been

possible to carry out this operation at high speed due to the danger to the hands of the 20 operator and to the fact that the pipe re-entered the rolls when high speed rolling was attempted.

By my invention these disadvantages have been entirely overcome and by its use sheet 35 metal pipe may be rolled in high speed power-driven rolls, thus greatly increasing speed of production and lowering manufacturing cost.

What I claim as my invention is:

In apparatus for rolling sheet metal pipe, the combination with the frame of the apparatus, and the rolls mounted therein, of a stock supporting table supported by the frame and inclined downwardly and forwardly from the entrance to the rolls, an apron rigidly secured upon the frame and forming a protecting cover for the top and front of the upper roll, said apron formed at its lower front edge with a forwardly 40 disposed step located in front of the entrance to the rolls, the front flange of said step extending into spaced relation above the table to form a gap between the table and said flange.

MURDO JOHN MUNRO.
